UNITED STATES PATENT OFFICE.

MARY A. WILLIAMS, OF KANSAS CITY, MISSOURI.

COMBINED CORSET AND BREAST-PAD.

SPECIFICATION forming part of Letters Patent No. 406,491, dated July 9, 1889.

Application filed April 1, 1889. Serial No. 305,596. (No model.)

To all whom it may concern:

Be it known that I, MARY A. WILLIAMS, a citizen of the United States, residing at Kansas City, in the county of Jackson and State 5 of Missouri, have invented certain new and useful Improvements in Combined Corsets and Breast-Pads; and I do hereby declare the following to be a full, clear, and exact description of the invention, such as will enable others skilled in the art to which it appertains to 10 make and use the same.

My invention relates to an improvement in combined corsets and breast-pads.

The object is to provide a set of breast- 15 pads which are used in combination with a set of corsets of peculiar construction.

A further object is to provide a set of breast-pads which shall be pleasant to wear and which will readily adapt themselves to 20 the person of the wearer and present an outward appearance such as a well-developed natural bust would present.

With these ends in view my invention consists in certain features of construction and 25 combination of parts, as will be hereinafter described, and set forth in the claims.

In the accompanying drawings, Figure 1 represents one of the breast-pads in position in the peculiarly-formed corset, the companion 30 pad and fastening-straps being omitted to show the construction of the corset. Fig. 2 represents a set of the pads detached from the corset, and Fig. 3 represents a transverse section through one of the breast-pads.

35 A represents a set of corsets provided at the upper portion of the front with cut-away portion, as shown at a, at points in front of the positions of the breasts of the wearer, and provided along the margin of said cut- 40 away portions with a series of eyelets a'.

B represents one of a pair of similarly-constructed breast-pads. The pads B are hemispherical in form and are constructed of some suitable elastic material, preferably of 45 rubber. The material of which the pad is constructed is intended to be thick enough to hold its shape and to return to its shape when from any cause it has been pressed out of shape and the pressure removed. The

pads are not inflated, and are provided with 50 manifold perforations b to render them cool and pleasant to the wearer. For the purpose of affording a convenient means of fastening the pads to the corset or dress, and for the further purpose of giving the base of the pad 55 an extended bearing upon the body of the wearer to render it easy, I provide the pads with a laterally outwardly-extending flange b' around the margin of the base. Through this flange b', I form eyelet holes b² as a convenient means of fastening the pad to the corset or dress. I find it convenient to secure the pad to the corset by a soft fine piece of tape or cord C, run in and out through said eyelets. I further find it convenient to secure 60 the pads to each other by one or more elastic straps or cords D, and also to provide the upper edges of the pads with shoulder-straps d, which may be fastened at the back to the back of the corset, or, in case the corsets are not worn, to the dress-waist, the 65 lower edges of the pads being in such case also attached to the dress-waist in front.

By cutting away that portion of the corset which commonly occupies a position in front 75 of the breast-pad the overheating due to an exclusion of the air from the pad and an additional thickness of material is avoided, and, furthermore, the breast-pad will present a 80 much more comely and natural appearance beneath the dress than where it is distorted or interfered with by the top of the corset.

Having thus fully described my invention, what I claim as new, and desire to secure by Letters Patent, is—

1. The combination, with a corset having cut-away portions opposite the breasts of the wearer and provided with eyelet-holes in the marginal walls of the cut-away portions, of hollow hemispherical perforated pads formed 90 with a laterally-projecting flange b', having eyelet-holes registering with the eyelet-holes of the corset, tape or cord passed through each series of eyelet-holes for securing the pads to the corset, and shoulder-straps secured to said pads, substantially as set forth.

2. The combination, with a corset having the portions opposite the breasts of the wearer

cut away and provided with a series of eyelet-holes, of pads having laterally-projecting flanges provided with eyelet-holes registering with the eyelet-holes of the corsets, the said flanges seated behind the margins of the cut-away portions of the corsets, and a tape or cord laced through the eyelet-holes of the corsets and flanges of the pads, substantially as set forth.

In testimony whereof I affix my signature in the presence of two witnesses.

MARY A. WILLIAMS.
